HIGH SIDE PRESSURE CONTROL FOR REFRIGERATION SYSTEMS

John N. St. Pierre, North Syracuse, N.Y., assignor to Carrier Corporation, Syracuse, N.Y., a corporation of Delaware

Filed Feb. 20, 1959, Ser. No. 794,669

5 Claims. (Cl. 62—184)

This invention relates to a control for refrigeration systems and more particularly to means for controlling the high side pressure in a refrigeration system.

In refrigeration systems, the portion thereof which operates at substantially discharge gas pressure is considered the high side. This usually includes the condenser, hot gas line, liquid line and the receiver. The portion of the system that operates at substantially suction gas pressure is considered the low side and usually includes the evaporator and the suction line.

It is common to operate commercial refrigeration systems throughout the year. Very often, such refrigeration systems include air cooled condensers. In such situations, the condenser is located out of doors and is subject to a wide variation of ambient temperatures. During periods when the ambient temperature is very low, the condensing pressure within the air cooled condenser drops to an extremely low level resulting in the poor feed of liquid refrigerant from the high side through the expansion means into the low side of the refrigeration system.

Various devices have been proposed to overcome these poor operating characteristics which result during periods of low ambient temperatures. One of the devices includes the use of a bypass around the condenser whereby the hot gas discharge line pressure is directly utilized for providing the motivating force for urging liquid refrigerant in the receiver through the expansion means into the low side of the refrigeration system. Another device which has been proposed consists of a plurality of face dampers which restrain the passage of air over the heat exchange surface of the condenser thereby drastically reducing the heat exchange between the coolant air and the refrigerant passing through the condenser.

In the case of the bypass around the condenser, it has been found that a substantially larger amount of refrigerant is required in the system than is normally needed; so the pressure control required in this system causes a higher initial cost of the system. With respect to the face dampers, the operation of such dampers is problematic being subject to frequent breakdowns and the initial cost of the system is also high.

The chief object of the present invention is to provide a refrigeration system having an improved control for maintaining high side pressure.

Another object of the invention is to provide a refrigeration system wherein the amount of air passing over the condenser is regulated in response to the high side pressure.

A further object is to provide a refrigeration system having a condenser through which air is passed by a fan connected to an induction motor and including means for varying the speed of the induction motor in response to the high side refrigerant pressure. Other objects of the present invention will become more apparent from the following description.

This invention relates to a refrigeration system including in combination a compressor, a condenser, a re-

ceiver, expansion means and an evaporator connected in a circuit. A fan driven by an induction motor is provided for passing air over the condenser in heat exchange relation with the refrigerant passing therethrough and means are provided for varying the volume of air passed over the condenser in response to the pressure of the refrigerant in the condenser by decreasing the fan speed by a decrease in voltage across the motor terminals.

10 The attached drawing is a schematic view of a refrigeration system embodying the present invention.

Referring to the drawing, there is shown a refrigeration system which includes a compressor 2 having extending therefrom a hot gas discharge line 3 which is connected to a condenser 4. A liquid line 5 extends from the condenser 4 to a receiver 6. The receiver 6 collects liquid refrigerant from the condenser. This liquid refrigerant passes through the expansion means 7 into the evaporator 8 wherein the refrigerant is substantially vaporized and returns through the suction line 9 to the compressor 2.

The expansion means may be the usual thermal expansion valve which includes a capillary line 10 which connects the valve and a temperature sensing bulb 11 located on the suction line. If it is desired, other types of expansion devices may be used such as capillary tubes.

With respect to the condenser 4, the drawing discloses a condenser which includes a hot gas manifold 15 which is connected to a liquid manifold 16 by means of a plurality of serpentine coils 17. These coils 17 substantially define the heat exchange surface of the condenser.

Normally, there is associated with heat exchangers such as the condenser 4 and the evaporator 8, one or more air moving means such as fans. In the present drawing the fan 20 is operatively associated with the condenser 4 and if it is desired, suitable fans may be used with the evaporator 8.

It is well known that in a given refrigeration system under a given load the head or high side pressure is related to the condensing temperature of the refrigerant within the condenser. The condensing temperature is usually governed by the temperature of the coolant acting upon the condenser to abstract heat from the refrigerant gas which is discharged into the condenser through the hot gas discharge line extending from the compressor. If the temperature of the coolant which is in heat exchange relation with the refrigerant gas passing through the condenser falls to a low temperature, a decrease in the head or high side pressure results. This decrease in pressure will lessen the rate of feed of refrigerant through the expansion device and thereby deleteriously affect the operation of the refrigeration system.

It is envisioned that the refrigeration system which comprises the present invention will be used under circumstances where the condenser will be remote from the evaporator, that is, the condenser is an air cooled condenser which will normally be located out of doors. The evaporator will normally be located adjacent some heat load within a given structure.

Under such circumstances, during certain times of the year when a low ambient temperature is experienced, the previously noted loss in head pressure will also be experienced resulting in the poor operation of the refrigeration system. In order to achieve satisfactory operation of the refrigeration system under such circumstances, the present invention visualizes decreasing the amount of coolant air which is passed into heat exchange relation with the refrigerant passed through the plurality of serpentine coils 17. This is achieved by varying the speed of the fan 20.

It is well known that varying the speed of alternating

current motors is extremely difficult. The present invention envisions utilizing a reactor which is a variable inductance in series with an induction motor to achieve low speed or variable speed of the fan 20.

The motor 25 is connected to the fan 20 and includes a rotor 26 which may be of the customary squirrel cage type. In the drawing there is shown, a single phase motor which includes the run winding 27 and the start winding 28. The motor shown is of the type wherein the start windings are maintained in the circuit during normal operation and in order to achieve a phase shift the start winding 28 has located in series therewith, a capacitor 36.

Considering the electrical circuit of the motor 25, the motor is connected by means of the lines 30 and 31 to a source of single phase alternating current. The line 30 is connected to the windings 27 and 28. The opposite end of the winding 27 is connected to the line 35. The other end of the winding 28 is connected to the line 34 which as previously noted, includes therein the capacitor 36. The line 34 joins the line 35 which terminates at the reactor 32' which is a variable inductance including a coil 32 which in the present application has an iron core. In order to achieve variation of this inductance, a pivoted contact lever 33 is pivotally mounted at 45 and is so constructed that contact may be made with the windings of the reactor 32' over a plurality of points thereby providing a large number of contacts and thereby a large gradation of inductances. The line 31 is connected to the contact lever 33 at the point 45.

In order to vary the inductance of the reactor 32', a suitable pressure responsive element 40 is associated with the reactor. This pressure responsive element includes a bellows 42 which acts against a bias spring 43. The bellows 42 is connected to the contact lever 33 by means of the member 44 so that any motion in the bellows will be reflected in the rotation of the contact lever 33 and the consequent variation in inductance in the motor circuit.

The bellows 42 is connected by means of a line 41 to the hot gas manifold of the condenser 4. It will be immediately appreciated that any variations in the condensing pressures of the condenser 4 will be sensed by the bellows and reflected in a change of the inductance which is in series with the windings of the motor 25.

Considering the operation of the present invention, current is passed through the lines 30 and 31 and the contact lever 33 is in a position so that the entire inductance of the reactor is substantially removed from the electrical circuit of the motor 25. The current passes through the winding 27 and similarly passes through the starting circuit which includes the capacitor 36 and the start winding 28.

Because of the phase shift provided by the capacitance in the starting circuit, the single phase motor will begin to rotate and operate at a speed slightly less than the synchronous speed of the motor field.

Considering the refrigeration circuit, the compressor 2 discharges refrigerant gas through the hot discharge gas line 3 into the hot gas manifold 15 of the condenser 4. Under normal circumstances the gas will pass into the serpentine coils 17 and be in heat exchange relation with the coolant air being passed over the serpentine coils 17 by the fan 20. The gaseous refrigerant is substantially liquified in the serpentine coils and collected in the liquid manifold 16. This liquid refrigerant is passed through the liquid line 5 and collected within the receiver 6. This liquid refrigerant then passes from the high side through expansion valve 7 into the low side which includes the evaporator 8. The refrigerant as it passes through the expansion valve will experience a pressure reduction which will cause the refrigerant as it enters the evaporator 8 to form cool liquid and gaseous refrigerant. This refrigerant liquid is subsequently vaporized in the evaporator. This gaseous refrigerant then

leaves the evaporator 8, passes through the suction line 9, and returns to the compressor 2.

When the ambient temperature decreases to an extremely low temperature the operating pressure of the high side will greatly decrease and will lessen the refrigerant feed through the thermal expansion valve 7 resulting in the unsatisfactory operation of the refrigeration system. In the present invention, however, this decrease in condensing pressure is sensed by the pressure responsive control 40 which is in communication with the hot gas manifold of the condenser 4 by means of the line 41. This decrease in pressure will cause the bellows 42 to shrink in response to the decrease in pressure. This, consequently causes the contact lever 33 to move to the dotted position shown in the drawing. This movement of the contact lever introduces an increasing inductance in series with the induction motor 25.

The reactor is an energy storing device and not an energy dissipating device so that the voltage decreases across the motor terminals without any loss of power in the system.

It is well known that the torque of an induction motor varies proportionately to the square of the voltage across the motor terminals. Likewise, it is known, that the torque requirements of fan and other air moving devices increases with speed. It is also known that the torque characteristics of a motor, start at a given torque for locked rotor conditions and increase with speed until a maximum is reached whereupon the torque sharply decreases until a no torque condition is reached at synchronous speed.

By introducing the inductance in the circuit which provides a voltage drop in the supply line there is a consequent reduction in voltage across the motor terminals.

Since as previously noted, motor torque is proportional to the square of the voltage across the terminals, there will be a decrease in speed of the motor. This decrease in speed will diminish the amount of coolant air placed in heat exchange relation with refrigerant passing through the condenser 4. Accordingly, there will be a tendency of the refrigerant in the condenser to reach normal condensing temperatures and pressures to maintain an adequate feed of refrigerant through the thermal expansion valve into the evaporator.

By means of a reactor or variable inductance and a head pressure responsive element, the present invention permits satisfactory operation of the refrigeration system under conditions where low ambient temperatures may cause deleterious effects on the high side pressure of a refrigeration system. This is achieved with relatively inexpensive parts and makes use of normal components used with a refrigeration system such as a squirrel cage induction motor. This is also achieved without the use of expensive face dampers or expensive bypass systems wherein large amounts of refrigerant are needed to compensate for flooding conditions which occur in the condenser when a bypass is utilized.

While I have described a preferred embodiment of the invention, it will be understood the invention is not limited thereto since it may be otherwise employed within the scope of the following claims.

I claim:

1. In a refrigeration system, the combination of a compressor, a condenser, a receiver, expansion means and an evaporator connected in a circuit, the condenser comprising a hot gas header having a plurality of heat exchange surfaces extending therefrom with refrigerant paths passing therethrough, said heat exchange surfaces being connected to a liquid header, at least one fan for passing air into heat exchange relation with the condenser, said fan being connected to an induction motor, a variable inductance being connected in series with said induction motor, and means responsive to the pressure of the refrigerant passing through the condenser, said pressure responsive means being operatively connected

with said hot gas header and with said variable inductance whereby when the pressure in the condenser decreases to a predetermined point the variable inductance connected in series with the induction motor increases the amount of inductance in the circuit to decrease the volume of air passing into heat exchange relation with the condenser by decreasing the fan speed permitting the pressure of the refrigerant in the condenser to increase.

2. In a refrigeration system, the combination of a 10 compressor, a condenser, expansion means, and an evaporator connected in a circuit, said condenser including a heat exchange coil with a path for refrigerant therethrough; fan means for passing air over said heat exchange coil for condensing refrigerant vapor passing 15 therethrough; an induction motor connected to said fan means; a variable inductance connected in series with the induction motor for varying the speed of the fan means; pressure responsive means; means connecting the pressure responsive means with the heat exchange coil to impose refrigerant pressure upon the pressure responsive means, and means operatively connecting said pressure responsive means to the variable inductance whereby a decrease in refrigerant pressure increases the amount of inductance in series with the induction motor to decrease the amount of air passing over said heat exchange coil by decreasing the speed of said fan means.

3. A refrigeration system as in claim 2 wherein said pressure responsive means comprises a bellows.

4. A refrigeration system as in claim 3 wherein said bellows is expanded in one direction upon an increase in refrigerant pressure in the condenser and is spring biased in an opposite direction upon a decrease in pressure to collapse the bellows.

5. In a refrigeration system, the combination of a compressor, a condenser, expansion means, and an evaporator connected in a circuit, said condenser having a heat exchange coil through which refrigerant passes, fan means for passing air into heat exchange relation with the condenser, said fan means being connected to an electric motor, a variable inductance connected in series with said motor, pressure responsive means, means connecting said pressure responsive means with said condenser, and means connecting said pressure responsive means with said variable inductance whereby when the pressure in the condenser decreases to a predetermined point the variable inductance connected in series with the electric motor increases the amount of inductance in the circuit to decrease the volume of air passing into heat exchange relation with the condenser by decreasing the speed of the fan means permitting the pressure in the condenser to increase.
